Frank S. Fithian,
INVENTOR

BY Victor J. Evans

ATTORNEY

UNITED STATES PATENT OFFICE

FRANK S. FITHIAN, OF CAMDEN, NEW JERSEY

NECKTIE APPLIANCE

Application filed August 16, 1929. Serial No. 386,290.

The object of this, my present invention, is the provision of an extremely simple, inexpensive and thoroughly efficient means for guiding and for causing the free movement of the neck band of a scarf or tie that is directed through a turnover or fold collar, so that injury to either the collar or the tie will be prevented and the tie can be knotted or tied in a better manner than when the neckband thereof binds between the folds of the collar.

To the attainment of the foregoing the invention consists in the improvement hereinafter described and definitely claimed.

In the drawing:

Figure 1 is a perspective view of my improvement in applied position.

Figure 2 is a front elevation of the improvement.

Figure 3 is a top plan view thereof.

Figure 4 is a sectional view on the line 4-4 of Figure 2.

While not disclosed by the drawing my improvement is designed to be arranged between a fold or turnover collar at the rear thereof.

The improvement comprises essentially resilient plates 1 and 2, respectively. The plate 2 is of a greater length and also of a greater width than the plate 1. The plate 2 provides the rear element of the improvement. Both the plates 1 and 2 are bowed, as disclosed by Figures 2 and 3 of the drawing and have their ends connected by eyelets or similar means 3. It is to be noted that the eyelets or fastening means pass through the upper corners of the plates 1 and 2 and that the said fastening means also pass through spacer elements, such as washers 4 so that the ends of the plates 1 and 2 are not brought into direct contact with each other.

Preferably the plates 1 and 2 are constructed of celluloid as are the spacer members 4. By providing the plate 2 of a

greater length and width than the plate 1 the lower edge of the plate 2 will depend a considerable distance below the plate 1 which affords a guide for directing the neck band of a tie or scarf between the said plates. 50 The spacer washers 4 prevent the ends of the plates from exerting an undue frictional engagement against the neckband so that when the device is inserted between the folds of a collar the neckband can be freely guided between such folds by virtue of the improvement and the tie or scarf can be knotted in a better manner than could be accomplished were my improvement not employed. 55 Because of the different lengths of the plates and the bowed or arcuate formation thereof, the outer and longer plate 2 assumes a greater curvature than the inner plate 1, so that the distance between the plates gradually decreases from the center to the connected corners thereof. This will properly hold the inner and outer folds of the collar spaced from each other, and will more effectively permit of the neckband being drawn between the plates 1 and 2. The inner plate 1 being of a less width than the outer plate 2 is disposed above the button opening in the collar so that the collar button does not contact with the improvement and, therefore, has no tendency to bind or to force the plate 1 against the plate 2 to cause the said plates to exert a binding action against the band of the necktie. 70

The simplicity of the invention and the advantages will, it is thought, be readily apparent so that further detailed description will not be required.

Having described the invention, I claim:

1. A guide for the neck bands of scarfs or ties which is passed through the folds of a turnover collar, comprising an inner and an outer arched resilient plate that have their ends, at their upper corners, connected but spaced away from each other, and the distance between the plates being greatest 85 90

at the center thereof and gradually decreasing therefrom to their connected ends.

2. A guide for the neck bands of scarfs or ties which is passed through the folds of a turnover collar, comprising an inner and an outer arched resilient plate that have their ends at their upper corners connected but spaced away from each other, and the outer plate being both of a greater length and width than the inner plate, and whereby the distance between the plates gradually increases from their connected corners to the center of the plates.

In testimony whereof I affix my signature.

FRANK S. FITHIAN.
